[57] CLAIM

The ornamental design for a foldable treadmill, as shown and described.

DESCRIPTION

FIG. 1 is a perspective view of a foldable treadmill embodying our new design, the perspective being viewed from the left and above with the treadmill in operating position; FIG. 2 is a left side view thereof; FIG. 3 is a right side view thereof; FIG. 4 is a front elevational view thereof; FIG. 5 is a rear elevational view thereof; FIG. 6 is a top plan view thereof; FIG. 7 is a bottom plan view thereof; and FIG. 8 is a perspective view similar to FIG. 1, showing the foldable treadmill in a folded position.
